[57] ABSTRACT

A moisture proof hollow electrical component such as a microwave antenna the interior of which is filled with a closed-cell, foam-in-place, low-density retarded polyurethane plastic substance having a specific dielectric constant approximately equal to that of the air which it replaces, thereby preserving the original electrical impedance characteristics and hence maintaining the operating efficiency of the antenna.

MOISTUREPROOF MICROWAVE ANTENNA**CROSS REFERENCE TO RELATED APPLICATION**

The present application is a continuation-in-part of application Ser. No. 767,884 filed Aug. 27, 1968 and now abandoned.

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

Many high-frequency antenna arrays are formed as a complex network of hollow radiating elements of elongated configuration and restricted diameter arranged symmetrically about a central point at which a common electrical feed member is located. In many cases, this antenna feed member is also of hollow configuration, and is coupled to the transmission line which leads to the antenna by means of a so-called Balun connector. The antenna may or may not include a reflector to control the direction in which the emitted energy is propagated.

Assemblies of the above type are subject to malfunction in the presence of moisture. This is primarily due to the fact that the structure "breathes" during changes in atmospheric pressure, and water vapor is consequently drawn into the hollow elements of the unit. This vapor then condenses and adversely affects the electrical characteristics of the antenna. Attempts have been made to seal the joints with various compounds, but this has not proven satisfactory when the customary plastic-to-metal interfaces are present.

Invasion of moisture into microwave antennas of the nature described may be prevented by originally designing the structure to incorporate a satisfactory filler material which is embodied into the unit during manufacture. This material is of course chosen to be compatible with the particular electrical and mechanical characteristics of the particular assembly into which it is introduced.

However, when it is desired to protect an existing structure from the presence of interior moisture, the problem is a serious one. The expedient of pressuring the antenna with an inert gas (such as argon or nitrogen) was attempted, but leakage could not be prevented and the structure retained the gas only for a short period of time. It was then suggested that the cavities be filled with a high-density foam, but this resulted in an impedance mis-match in the antenna and seriously degraded its performance. This could have been avoided by employing a compensating transformer, but such extra component not only adds to the cost of the apparatus but introduces an additional source of potential malfunction.

SUMMARY OF THE INVENTION

In accordance with a feature of the present invention, the basic concept of filling the hollow portions of an existing microwave antenna with a moisture-excluding substance is retained, but the procedure is modified to take into account the necessity of maintaining the electrical efficiency of the assembly following such

modification without adding separate components such as the transformer mentioned above. In order to achieve optimum results, three factors have been given consideration. There are (1) the choice of a filler material such as polyurethane plastic of the rigid, closed-cell, freon-blown, foam-in-place type having a specific dielectric constant chosen in accordance with the antenna's electrical characteristics, (2) the addition of a retarding agent to the mixture prior to insertion into the antenna cavities, so that the composition may be injected as a liquid capable of flowing over the internal surfaces to wet all areas of the latter before hardening of the material occurs, and (3) imparting to the plastic material a high expansion rate so that each hollow antenna region is certain to be completely filled by the foam after expansion of the latter has taken place.

One object of the present invention, therefore, is to provide a moistureproof and electrically insulated microwave antenna, as well as the connection between such antenna and the transmission line leading thereto.

Another object of the invention is to provide a high-frequency, multipolarized antenna which is highly resistant to the entry of moisture under adverse environmental conditions, such for example as temperatures in excess of 200° F., where certain thermoplastic substances, such as polystyrene, cannot be employed.

A further object of the invention is to provide a cubic antenna array in which each radiating element is completely filled with a moistureproof substance, the electrical characteristics of which are chosen to match those of the antenna, whereby a high level of operating efficiency is maintained.

Other objects, advantages, and novel features of the invention will become apparent from the following detailed description of the invention when considered in conjunction with the accompanying drawings wherein:

BRIEF DESCRIPTION OF THE DRAWINGS

FIG. 1 is an exploded perspective view of a microwave antenna of the type to which the present invention is particularly adaptable;

FIG. 2 is a sectional view of the antenna of FIG. 1 taken along the line 2-2 after this portion of the antenna has been filled with the particular moistureproofing foam of the present invention; and

FIG. 3 is a further sectional view of the assembled antenna of FIG. 1 taken along the line 3-3, showing the regions filled with foam after the process of the present invention has been completed.

DESCRIPTION OF THE PREFERRED EMBODIMENT

Before describing the details of the present concept, it should be emphasized that the structural characteristics of the particular antenna to which the moistureproofing method herein set forth is to be applied form no part of the invention, and that the novel aspects of applicant's process are equally adaptable to all forms of microwave radiators so constructed as to possess one or more hollow energizable components, or so designed that the electrical connection to a transmission line is open to the entry of moisture under severe or extended exposure to the weather. The particular antenna chosen for illustration is purely exem-

plary of such a class of radiators, and hence an extended discussion of its constructional details will be omitted as unnecessary to an understanding of the unique features of applicant's moistureproofing process.

The microwave device of the drawings represents a so-called "agave" antenna of the cubic type — that is, it is made up of four similar radiating units 10, 12, 14 and 16 arranged in quadrature. The active element of each such unit is a hollow sector or cavity (such as 18 in FIG. 1) from which projects a rod 20 the terminal portion 21 of which is threaded as shown. This rod 20 extends through a hollow cylindrical member 22 to which is attached a pair of brackets or straps 24 designed to support the active element 18 in place after the latter is welded or bolted thereto. An insulating bushing 26 is interposed between the members 18 and 22 when the unit is in assembled position.

The four units 10, 12, 14 and 16 lie generally in a single plane which in FIG. 2 is that of the paper. Extending normal to this plane and through the central axis of the device is a so-called "driver" assembly, the principal component of which is a hollow tube 28 (FIG. 1) one end of which is flanged at 30 and the other end of which supports a microwave director (generally identified by the reference numeral 32) the purpose of which is to create a particular directivity pattern for the antenna in a manner well known in the art. The unit 32, both as to its construction and electrical characteristics, has no bearing on the invention as herein set forth, and is mentioned merely for the sake of completeness. A plurality of bolts 34 secure the director 32 to the tubular member 28 when the antenna is in assembled condition.

A hollow hub 36 encircles the tubular member 28 and is formed with four radially-extending arms 38, 40, 42 and 44. These arms respectively support and position the four hollow cylindrical members (such as 22) through which respectively extend the four threaded rods (such as 20) to each of which an active radiating member is attached. It is to be noted that the outer diameter of each threaded rod 20 is less than the inner diameter of the radially-extending arm through which it passes, thereby forming a plurality of cavities 46, 48, 50 and 52 which are annular in cross-section and which are particularly susceptible to the entry of moisture after the antenna has been assembled.

Also shown in FIG. 1 is a so-called Balun unit generally identified by the reference numeral 54. It consists essentially of a plurality of electrical conductors secured to a flange 56 designed to abut the flange 30 when the antenna is assembled. Receivable in the tubular member 28 are four conductors 58, 60, 62 and 64 the length of which is chosen so that the extremities thereof lie within the hollow hub 36 when assembly of the antenna is complete. The ends of the conductors are threaded and bent at an angle of 90°, so that each conductor lies in a position to receive one of the rods 20 when the latter is inserted into its associated hollow cylindrical member 22. The rod is then screwed into the proper one of conductors 58-64 to establish a tight electrical connection therebetween.

Two of the conductors 58-64 extend through the flange 56 to become associated with a transmission line (not shown) leading to the transmitter/receiver with

which the antenna is associated. The remaining two of the conductors are grounded to the flange, the dimensions of the Balun unit being chosen so that the flange is located at a point where the current and voltage relationships permit such action to be taken. Reference to FIG. 3 of the drawings shows the two flanges 30 and 56 secured in face-to-face position by the bolts 66.

Since the conductors 58-64 of the Balun unit 54 are physically spaced from one another in order to preclude electrical interaction therebetween, a number of gaps or spaces are formed within the tubular member 28 between the inner wall of the latter and the outer surfaces of the respective conductors. This portion of the antenna, like that in the vicinity of the rods 20, is particularly susceptible to the entry of moisture due to "breathing" with changes in atmospheric pressure.

The device described above is an example of an existing multi-polarized UHF antenna of a type now in extensive use. It was originally designed for optimum operating efficiency — in other words, the electrical components of the antenna were matched to the dielectric materials employed. In the case selected for illustration, the dielectric substance used (the "filler" material) was air. If this "low" dielectric material is changed to one of appreciably higher value, it is necessary to modify the diameter of the Balun conductors 58-64 or to add a compensating transformer as discussed above. Attempts heretofore made to moistureproof the antenna by adding an ordinary filler material without considering the factors involved invariably resulted in a severe impedance mis-match and a consequent drop in operating efficiency. The present concept recognizes that certain conditions must be met, and sets forth specific procedures by means of which the desired results can be obtained.

If the air which originally filled the open spaces within the antenna is to be replaced by a moistureproofing material, then the electrical characteristics of such added material must closely approximate those of the air which it replaces. Furthermore, the moistureproofing material must be capable of completely filling all those regions where entry of moisture has been shown to be undesirable, and to be of such a nature as not to add appreciably to the overall weight of the antenna.

One substance which has been found to be especially suitable for the purpose consists of a freon-blown foam-in-place polyurethane plastic of the closed-cell type, having a relatively low density. The electrical properties of such a substance may be selected so that the specific dielectric constant of the material closely approximates that of the air which it replaces. In the case under consideration, the relative permittivity of the plastic filler, when the latter is formulated in a manner to be later set forth, is 1.058 at 9.375 KMC, with a loss tangent of 0.00048. Thus impedance mis-match is avoided, and operating efficiency maintained.

One substance especially suitable for the purpose of the present invention is made up of the following components in the proportions set forth:

	P.B.W.
Component A	
Propoxylated sorbitol (Atlas G2408)	100.0
Toluene diisocyanate, 80/20 (TDI)	390.0
Component B	
Propoxylated sorbitol (Atlas G2408)	100.0
Triethylenediamine (DABCO)	0.8

Silicone oil (Union Carbide L5320)	1.0
Phosphoric acid, 85%	0.4
Fluorocarbon 11 B (Freon)	35
Ratio: 100 parts Component A: 70 parts Component B	

The above-described formulation yields a halocarbon-blown, polyether/TDI, rigid urethane foam with a nominal density of two pounds per cubic foot and dielectric constant of 1.058.

An alternative substance which may be employed if desired in place of the one above described is that manufactured by the Olin Chemical Corporation of New York City under the designation Polysystem 402-0771. It is made up of a polyhydroxyl blend component and a prepolymer (polyol and tolylenediisocyanate) component which, when mixed at a 1:1 pbw (parts by weight) ratio, produce a foam of approximately 2 lbs/ft³ free rise density. The polyhydroxyl resins used in both components are polyether base type materials, with the polyol component containing trichlorofluoromethane with minor amounts of silicone and an amine catalyst.

In preparing the antenna of the drawings for moistureproofing or waterproofing in accordance with the present invention, the antenna, as well as the resin and its catalyst, should be at an ambient temperature of approximately 85° F. A pressure gun is used for injecting the substance into the antenna cavities, and, if this gun is designed to accommodate an 8-oz. polyethylene cartridge, then a number of cups (say five, for example) are filled with 120 grams each of Component A, and a similar number of cups are filled with 84 grams each of Component B (a 10:7 ratio). This amount (when mixed) has been found to be sufficient to fill all the cavities of a single antenna except those of the radiating dipoles per se. These elements are filled separately, as described hereinafter.

One cup of Component B is then poured into a cup of Component A (after a retarding agent has been added to the latter, as hereinafter described) and the substance thoroughly mixed. The gun cartridge is then filled with this mixture.

Before proceeding further with a description of the waterproofing process, it should be mentioned that the antenna of the drawings is provided with an injection hole 68 (FIGS. 1 and 3) and four "bleed-out" openings 70 respectively formed in the insulating bushings 26. The injection hole 68 should be dimensioned to accommodate the nozzle or tip 71 of the pressure gun 72 containing the foam cartridge.

The contents of the cartridge are injected into the opening 68 as shown in FIG. 3. It has been found in practice that five cartridges of foam are required to complete the operation, so it is preferable that two operators should work together, one mixing the ingredients and the other loading the cartridges and injecting the foam into the antenna. The process should be coordinated to take a minimum amount of time, so that previous injections of foam do not harden and block the passage before all of the foam has been inserted. After five injections of foam are made, the injection hole 68 is closed off. The foam in the antenna cavities then expands and forces some material out of each of the "bleeder" openings 70 in each arm. As soon as this occurs, each opening 70 should be blocked off for a short period of time (about 15 seconds) to allow the expanding foam to "back fill" in the cavities

and hence reach all regions to be moistureproofed. After the expiration of this 15-second period, remove all restrictions from the openings 68 and 70 and allow all excess foam to ooze out. After the foam has cured for about 12 hours, the excess is cleaned away from the openings.

Each dipole or radiating element 18 is filled with foam separately and independently of the operation described above. For such purpose, each such element 18 is provided with a pair of openings 74 and 76 located on opposite sides of the front edges (FIGS. 1 and 2). After a mixture has been prepared as described above, one cartridge of foam is injected into each element 18, the contents of the cartridge being evenly divided between the openings 74 and 76. Following each injection, the remaining hole should be blocked for a short period of time to permit expansion of the foam within the cavity and ensure a "wetting" of all interior surfaces.

FIGS. 2 and 3 of the drawings illustrate by stippling those regions of the antenna which are filled with foam following completion of the process set forth above. It will be noted that all of the air which formerly occupied the spaces between the electrical components has been replaced with foam and, since the latter is impervious to moisture, no shorting or other operating malfunction is likely to occur even under severe environmental conditions.

The material above described additionally contains a retarding agent which allows sufficient time to mix the components, insert the mixture into a pressure gun, and carry out the injection process. The retarding agent also maintains the plastic mixture in such form that it is capable of flowing around the internal elements of the antenna to wet all such surfaces before hardening occurs. Since the internal passageways of the antenna may be long and restricted in diameter, absence of a retarding agent may result in the foam hardening at or near the entry point before the cavity is completely filled. Presence of the retarding agent thus ensures sealing of the assembly at the critical points — those places where various components are joined together, and especially in the Balun feed unit. This aspect of the invention process is aided by the high expansion rate of the foam — some 30 to 1 in practice. One suitable retarding agent has been found to be benzoyl chloride, C₆H₅COCl, having a molecular weight of 140.57. This is mixed with Component A in a ratio of 1 part of retardant to 1,000 parts of Component A. It is important to note that unless the retarding agent is used, the injected foam will harden before all cavities are completely filled, and operating efficiency of the antenna will be lowered.

The fumes given off when the foam ingredients are mixed in the manner above described are toxic, and exposure thereto should be avoided. Chemical respirators are suggested for the operators, together with adequate ventilation in the work area. Plastic gloves should be worn and clothing protected against spillage. After the foam is cured, however, it can be handled in a normal manner.

It is emphasized that the chemical constituents of the plastic substance utilized in practicing the present invention are not critical, and that any material which exhibits the required physical and electrical charac-

teristics may be employed. The essence of the concept herein disclosed is the matching of the electrical impedance of the plastic which fills the antenna to the electrical impedance of the member into which it is injected. In fact, it has been found that when the respective electrical impedances of the plastic foam and the antenna into which it is injected are mis-matched by a ratio in excess of 1 to 1.1, the beneficial results obtained by practicing the disclosed method will not be obtained.

Although plastic waterproofing substances for microwave antennas are disclosed in the prior art, such disclosures completely lack any teaching that the dielectric constant of the plastic should approach zero. Hence antennas moistureproofed by such methods can not achieve the operating efficiency attainable by practicing the process herein set forth.

It should be recognized that applicant's process calls for the step of injecting into a cavity a plastic possessing a "relatively high expansion rate," so that the substance so injected will "expand within --- said cavity" to flow over the entire inner surface of the cavity and "wet" the same. This "expansion" feature of the plastic is extremely important to insure that the entire cavity is filled, and hence the plastic is injected under pressure. A pour-in-place foam, as suggested in the prior art, does not necessarily possess any expansion characteristics. Such a foam would not serve applicant's purpose regardless of its electrical properties. This "expansion" characteristic of the particular foam set forth herein insures that all of the air within the antenna is replaced with foam. Pouring prior art foam into an open container will not necessarily achieve this result, as no expansion is ordinarily required.

It is well known to all workers in the electrical art that the closer to unity impedance matching becomes, the more efficient is the operation of the device. Any reduction in mis-match is therefore highly desirable. It is a question of maximum power transfer, and a mis-match of as little as 1 to 1.24 significantly reduces the amount of energy that is available for utilization.

The substitution of polystyrene for the urethane material above described is not feasible, since the microwave antenna of the invention is intended to operate under adverse environmental conditions. This embraces all climatic variations, including bright sunlight. In practice, antennas exposed to the sun are heated by the impact of the sun's rays on the outer metal surfaces, raising the inner temperature to relatively high levels when such exposure continues for any prolonged period of time. Antenna heating also occurs due to the radiation of high-frequency energy from the active surfaces of the assembly, as well as from a terminal impedance mis-match of the type which the present invention is specifically designed to avoid. Antenna heating also results from discontinuities in the current path which affect the standing wave ratio critical points in the assembly. Reflections from nearby objects can also produce appreciable heating, and this condition is especially severe on board naval vessels in an environment where the antenna of the present invention has found widespread use. Many antenna constructions of the type herein discussed have actually "burned out" as a result of this heating. Although the exact temperature reached varies with antenna design

and input power levels, figures of above 200° F are not uncommon in practice.

The polyurethane foam described above adequately resists these high temperatures without adverse effects. 5 However, polystyrene foam will not. A brochure published by the Dow Chemical Company clearly states that —

"Because polystyrene is a thermoplastic material, styrofoam cannot be used where temperatures will exceed 175° F."

Furthermore, applicant has no knowledge of any foam-in-place polystyrene which is available to the public at the present time. Polystyrene is conventionally supplied in the form of beads which are molded in the 15 presence of heat. How such a material can be employed in the process specifically described by applicant is by no means clear, nor is it understood how such chemical can be injected under pressure into an antenna, following which it will foam in place and expand to "wet" the 20 entire inner surface of the assembly.

Obviously many modifications and variations of the present invention are possible in the light of the above teachings. It is therefore to be understood that within the scope of the appended claims the invention may be 25 practiced otherwise than as specifically described.

I claim:

1. A multipolarized microwave antenna of the type formed as a complex network of hollow radiating elements of elongated configuration and restricted diameter 30 which is subject to operational temperatures in excess of 175° F and having a plurality of cavities containing energizable components electrically isolated from one another, comprising

a. a dielectric material which precludes entry of moisture into said antenna and electrically isolates the energizable components from one another, completely filling each cavity of said antenna;

b. said dielectric material consisting of a foamed-in-place low-density polyurethane plastic substance having specific dielectric constant approximately equal to that of air but in no event exceeding 1.1, said plastic substance including a retardant and the following components in the ratio set forth:

		P.B.W.
45 Component A	Propoxylated sorbitol	100.0
	Toluene diisocyanate, 80/20	390.0
Component B		
	Propoxylated sorbitol	100.0
	Triethylenediamine	0.8
	Silicone oil	1.0
	Phosphoric acid, 85%	0.4
	Fluorocarbon 11 B	35

50 Ratio: 100 parts Component A to 70 parts Component B, said plastic substance having a dielectric constant of approximately 1.058, said retardant is benzoyl chloride in a ratio of one part thereof to 1000 parts of Component A; and

c. said plastic substance contacting the entire inner surface of each such cavity in a continuous and uniform manner without voids which otherwise lower the operating efficiency of the antenna, thereby completely filling and thus sealing the interior of such cavity from the entry of moisture, the presence of such plastic material as a dielectric between the said energizable components acting to maintain the electrical operating efficiency of the antenna by introducing an impedance characteristic essentially the same as that provided by air.

* * * * *
